DISPENSING PAPER PACKAGE

Duryea Bensel, New York, N. Y., assignor to
 Bensel Corporation, New York, N. Y., a corporation of Delaware

Application February 24, 1937, Serial No. 127,377

11 Claims. (Cl. 229—1.5)

The present invention relates to an improvement in dispensing packages, adapted for use in packeting sugar and the like in measured quantities, and such packages are more especially 5 adapted for containing and dispensing granulated, or loose, sugar in beverages, or elsewhere as desired.

Heretofore, lump sugar has been packed in wrapped paper containers or folders, for convenience in use at the table, for dispensing measured quantities of the same, to sanitarily protect such sugar, in handling, and to provide an advertising surface on the wrapped sugar.

The present improvement carries forward the above last noted advantages, but packages loose or granular sugar, which will freely flow from the package after the same is broken, with the advantage that the flowing loose sugar granules are not touched by the hand of the user, and the 10 loose sugar dissolves more readily in a beverage than does lump sugar. When a lump of sugar is unpackaged, it usually has to be touched by the fingers to completely remove the paper wrapper therefrom and thus, in the main, the object of 15 keeping the contained lump sanitary is defeated.

All forms of loose sugar, including confectioner's sugar and the like, may be packaged, in automatic packaging machines, thus eliminating the necessity of being contaminated by human 20 hands, to the point of actual discharge into a beverage, or other use.

The foregoing, and other features of advantage will be apprehended as the herein disclosure proceeds, and it will be obvious that modifications may be made in the structures herein disclosed without departing from the spirit hereof or the scope of the appended claims.

Briefly, the present improvement contemplates the use of a flexible paper wrapper of desired 25 form, which is filled with loose sugar, the package, when filled, being substantially non-rigid and flexible, whereby when broken, the sugar content 30 may be discharged, by squeezing, to empty the same, thus permitting the contents to be directly 35 discharged to its final disposition and use, without coming in contact with the fingers of the user.

In the drawing,
 Fig. 1 shows a sugar filled torpedo-like package 40 in elevation;
 Fig. 2 is a bottom view thereof;
 Fig. 3 is one form of the blank used to form 45 the package of Figs. 1 and 2;
 Fig. 4 is a front view in elevation, showing a 50 modified package structure;

Fig. 5 is a side view of Fig. 4;
 Fig. 6 is a blank to form the package of Figs. 4 and 5;

Fig. 7 is a fragmentary end view of the obverse 5 side of Fig. 4 showing the terminal wrap of the glue lap of Fig. 4;

Fig. 8 is a view in elevation of a further modified form of filled package;

Fig. 9 is a sectional view, taken on the lines 9—9, Fig. 8, looking in the direction of the arrows; and

Fig. 10 is a fragmented view of the blank for forming the package of Fig. 8.

The torpedo type of package of Figs. 1, 2 and 3, is made of a blank generally denoted by 1, Fig. 3, 15 the blank being preferably circular, though it may be of rectangular or other outline, upon the center of which a measured quantity of loose flowable sugar may be deposited, the marginal edges of the blank being treated with a suitable 20 adhesive, the outer margin being then evenly drawn upwardly about the sugar and the margin in excess of the sugar volume being then twisted tightly, as at 5, Fig. 1, to form a finger manipulating end, the adhesive on the margin sealing 25 the twist 5 and holding it in the twisted condition. The blank 1, Fig. 3, before filling with sugar, is pre-cut with a series of traversing lines of cut-scoring 2 and 3.

When it is desired to break the package thus 30 described, the twist is gripped between the thumb and forefinger of one hand, and squeezed, with the cut-scoring over the cup of beverage, and the cut-scores 2 and 3 are ruptured and the sugar caused to be discharged therefrom.

The cornucopia shaped package shown in Figs. 4, 5 and 7, is made from the triangular blank, generally denoted by 6, Fig. 6, which comprises the main triangular panel 9, having a glue lap 7, defined by a score line 8 from the panel 9, said 40 lap being provided with an adhesive 12, and having its lower end 11, extending in an outstanding extension, for purposes later to be described.

The upper top edge of the panel 9, including the top edge of the lap 7 is angled from the central apex 13, downwardly to the outer corners 14—15. The marginal edges of the angled edge 13—14—15 is also provided with an adhesive, indicated by 10—10, Fig. 6.

In making up the package of Figs. 4 and 5, 50 the blank 9 of Fig. 6 is folded over on its medial line, shown dash-dotted at 17, and then the glued lap 7 is over folded on the edge 18, as in Fig. 4. The extended lower end 11, is then wrapped around the lower apex A, as at 11, Fig. 7, and is 55

thus affixed to the obverse side of the package and effectively renders the apex A sift-proof.

Then the sugar, in desired, measured quantity is introduced at the upper open end of the 5 cornucopia, and the glued edges between 13, 14 and 15 and brought together flat-wise, as at 10, Fig. 5, and sealed to each other. Near the apex A, as in Figs. 4 to 7 inclusive, there is provided a line of spaced perforations 16, to form a rupture point, whereby the apex A below the line 16, may be first broken and the apex removed thus to form a pouring spout at the truncation so formed. Then the sugar is squeezed out, as described for Fig. 1.

15 It will be noted that the perforation line 16, in the blank 6, Fig. 6, is also angled from the axis line 17, so that the perforation line runs parallel to the glued flap closing edges 10-10. This is for the purpose of rendering both the edges 20 10-10 and the lines of perforation 16 to run straight across the cornucopia after the folding of the panel 9 on the axis 17.

In the modification in Figs. 8, 9 and 10, which is also a cornucopia, the blank 19, Fig. 10, is shown 25 fragmentary, with its apex broken away, but which latter is substantially the same as that described for Fig. 6, and which is shown in full in Fig. 8.

The main difference of the container of Fig. 8 30 is that it is not ovate in cross section, as is the container of Fig. 4, but it is circular in cross section, as indicated in Fig. 9. The container of Fig. 8 may be provided with a line of weakness at the line x-x, or it may be without such weakened line. Due to the cylindrical cross section of this modification and being well packed with sugar, the apex A may be broken across at line x-x by the rupture of the paper and the contents squeezed from the separated pieces.

40 The blank, Fig. 10, comprises a main panel 19, a glue lap 20 which may be defined therefrom by a score line 21, which lap section is provided with adhesive 27. The upper part of the blank 19 is provided with a curved marginal lap 23 45 defined therefrom by a curved score line 28, the marginal edge of said lap being coated with an adhesive 26, Fig. 10.

When the container is assembled by engaging 50 lap 20 with edge 22, with its upper end 23 left open, it is filled with sugar, and the lap 23 is then twisted to a closure 25, as in Fig. 8, and the adhesive keeps the twist intact.

When it is desired to empty the container, the apex A is broken away, the package squeezed, 55 and the contents caused to flow therefrom, until emptied.

Having thus described the invention what is claimed is:

1. A substantially cone-shaped package, for 60 loose dry flowable granular material, of substantially circular cross-section having a diameter substantially as great as half the length of the axis, and comprising a blank of limp paper adhesively sealed, and provided with an annular imperforate weakened line portion disposed around and symmetrically to the main axis of the package and strong enough to hold the contained material in ordinary use, said line being so disposed and weak enough to be ruptured and release the material, without rupturing the package elsewhere, when the package 65 adjacent to said line is squeezed together from opposite sides in directions toward said axis; said line being so disposed that when they are sufficiently ruptured, a wide opening is formed in the 70 75

package; the paper away from the weakened lines being strong enough to limit the rupture caused by said squeezing approximately to the vicinity of said line.

2. A package for dispensably containing loose 5 pulverulent material comprising a paper container made from a single blank, said container being finally sealed, after being filled with said material, by applying adhesive to the filling end thereof and twisting the said end to a tight closure, 10 and a preformed rupturable cut in a portion of said container, whereby squeezing the package, will rupture the same and form a material dispensing opening therein.

3. A package as set forth in claim 1, in which 15 the sealing thereof is accomplished after the application of adhesive, by bringing the adhesive portions together to form a flat sealed contact.

4. A package as set forth in claim 1, in which 20 the package is in the form of a cornucopia, said blank being in the form of a triangle having a glue lap on one angular edge thereof said lap having an extension beyond the apex of the blank, and when the blank is assembled to 25 package form, said lap extension is wrapped around the apex of the cornucopia to thereby seal said apex by a plurality of wrappings and render it sift-proof.

5. A package for loose granular material, 30 said package being completely closed and comprising a single piece of limp paper provided with imperforate weakened line portions strong enough to hold the contained material in ordinary use and weak enough to be ruptured and 35 release the material when the package of material is squeezed; said lines being so disposed that when they are sufficiently ruptured, a wide opening is formed in the package; said package being held in closed condition by having an end 40 tightly twisted and having adhesive on the inner face of the paper at said twisted end.

6. A package for dispensably containing loose 45 granular material, comprising a closed paper container made from a single blank, said container being adhesively sealed after filling with said granular material and having preformed, rupturable dispensing closed cut scores therein, sealing thereof being accomplished after the application of adhesive, by twisting the adhesived 50 portions together in a tight twist.

7. An article of manufacture and sale comprising a package approximately as thick as wide; loose dry flowable granular material substantially filling the package; said package being 55 composed of paper and adhesively sealed and completely closed at one end and provided substantially near the opposite end with weakened line portions disposed in walls of the package at thick parts thereof the weakened portions being 60 strong enough to hold the contained material in ordinary use, and being so disposed and weak enough to be ruptured and release the material, when the package of material is squeezed; said lines being long enough to give, when they are 65 sufficiently ruptured, a wide opening in the package; the package being of such shape, and the paper away from the weakened lines being of such strength, that the rupture caused by said squeezing is limited approximately to the vicinity 70 of said weakened lines.

8. An article of manufacture and sale comprising a package approximately as thick as wide; loose dry flowable granular material substantially filling the package; said package being composed 75

- of paper and twisted and sealed in the twist and completely closed at one end and provided substantially near the opposite end with weakened line portions disposed in walls of the package at thick parts thereof, the weakened portions being strong enough to hold the contained material in ordinary use, and being so disposed and weak enough to be ruptured and release the material, when the package of material is squeezed; the package being of such shape, and the paper away from the weakened lines being of such strength, that the rupture caused by said squeezing is limited approximately to the vicinity of said weakened lines.
9. An article of manufacture and sale comprising a package approximately as thick as wide; loose dry flowable granular material substantially filling the package; said package being composed of paper and flattened at one end and having the flattened parts sealed together to completely close said end; said package being provided substantially near the other end with weakened line portions disposed in walls of the package at thick parts thereof the weakened portions being strong enough to hold the contained material in ordinary use, and being so disposed and weak enough to be ruptured and release the material, when the package of material is squeezed; the package being of such shape, and the paper away from the weakened lines being of such strength, that the rupture caused by said squeezing is limited approximately to the vicinity of said weakened lines.
10. An article of manufacture and sale comprising a package; loose dry flowable granular material substantially filling the package; the package being approximately as thick as wide and completely enclosing said material and comprising a piece of paper provided with imperforate weakened line portions disposed in walls of the package at and adjacent to thick parts of
- the package, said line portions being remote from the opposite walls of the package, and strong enough to hold the contained material in ordinary use; said thick parts of the package being thick enough to allow the material to flow when the package of material is squeezed together from opposite sides near said line portions, thereby to crowd the material against the line portions to exert pressure on the line portions, said line portions being weak enough to be ruptured by said pressure and release the material; said lines being long enough to give, when they are sufficiently ruptured, a wide opening in the package for the exit of material; the paper away from the weakened lines being of such strength, that the rupture caused by said squeezing is limited approximately to the vicinity of said weakened lines.
11. An article of manufacture and sale comprising loose dry flowable granular material and a package approximately as thick as wide completely enclosing said material and comprising a piece of paper provided with imperforate weakened line portions disposed in walls of the package at and adjacent to thick parts of the package, the line portions being remote from the opposite walls of the package, and strong enough to hold the contained material in ordinary use; said thick parts being thick enough to allow the material to flow when the package of material is squeezed together from opposite sides near said line portions, thereby to crowd the material at the line portions and exert pressure on the line portions said line portions being weak enough to be ruptured by said pressure and release the material; the paper away from the weakened lines being of such strength, that the rupture caused by said squeezing is limited approximately to the vicinity of said weakened lines.
